UNITED STATES PATENT OFFICE

FRANK R. ZUMBRO, OF WAYNESBORO, PENNSYLVANIA, ASSIGNOR TO FRICK COMPANY, OF WAYNESBORO, PENNSYLVANIA, A CORPORATION OF PENNSYLVANIA

METHOD AND MEANS FOR MAKING CARBON DIOXIDE SNOW

Application filed January 23, 1929. Serial No. 334,564.

This invention relates to method and apparatus for manufacturing carbon dioxide snow or ice.

An object of the invention is to provide a system for making snow or ice from carbon dioxide which will operate more efficiently than machines now known.

A further object is to provide in a system for making carbon dioxide snow a cooling unit by means of which water in the carbon dioxide fluid will be frozen out thereby drying the carbon dioxide fluid.

Another object is to provide a system for making carbon dioxide snow which will operate at pressures lower than hitherto found necessary.

Other objects and advantages will appear as the description proceeds.

Referring to the accompanying drawing, which is made a part hereof and on which similar reference characters indicate similar parts,

The figure shows a complete snow manufacturing system using my invention.

In the manufacture of carbon dioxide snow and ice as hitherto carried out it has been found necessary to operate the system under enormously high pressures, this pressure seldom falling below 750 pounds per square inch. One difficulty of operating under pressures lower than this was that water contained in the carbon dioxide fluid became frozen at the expansion nozzle to the snow machine.

By means of a suitable cooling unit, such for example as that shown in my co-pending application Serial No. 333,559, filed January 19, 1929, for Liquid cooler, I am able to freeze out all water from the carbon dioxide fluid.

By this drying method the carbon dioxide fluid is rendered free from water which would freeze in the carbon dioxide line at the expansion nozzle. By using a cooling unit to dry the carbon dioxide liquid, I am able to operate the system under pressures lower than hitherto found necessary. In my system therefore, I have provided a reducing valve between the receiver in which the fluid is under high pressure and the cooler in which the fluid is cooled before its admission to the

snow machine. This feature is of considerable importance. By the removal of moisture from the carbon dioxide fluid in the cooler, and the operation at lower pressures, I am able to operate with a greater opening at the expansion valve on the snow machine than when the pressures are high, resulting in improved operation by permitting better adjustment. Furthermore pressure reduction results in a greater factor of safety in the apparatus.

In the drawing numeral 10 indicates a first stage compressor unit having an intake 11 and a discharge 12. The discharge line 12 leads to a second stage compressor 13, from which the fluid passes through a line 14 to a condenser 15. From the condenser the fluid passes to a receiver 16. The condenser 15 may be cooled in any suitable way as by means of a coil shown at 17, through which cooling fluid may be passed. From the receiver 16 fluid passes to a pipe 18 which branches, one branch 19 entering a cooling coil 20 in a liquid cooler 21. An expansion valve 22 controls admission of fluid from the pipe 19 to the cooling coil 20. Expanded fluid from the cooling coil 20 passes through a line 23 to the pipe 12 through which it passes to the intake of the second stage compressor 13. The pipe 18 has a reducing valve shown at 24, through which the pressure of the fluid in the receiver 16 is lowered before its entry into the cooler 21. From the cooler 21 the cooled carbon dioxide passes through a pipe 25 and an expansion valve 26 to a snow machine 27. Such of the fluid as is not frozen in the snow machine 27 passes to the line 11 through which it is drawn into the intake of the first stage compressor 10. From time to time if found necessary hot gas may be passed through this cooler to thaw the water from the coil 20. The water may be drawn off through the valve 28.

Instead of taking fluid from the line 19 I may take liquid from the cold liquid line 25 through a line 32 expanding it through a valve 33 into the coil 20 to cool the cooler 21.

The operation of the system should be apparent from the description which has just been given. Fluid is compressed, condensed

and delivered to a receiver 16 under high pressure. The pressure in the receiver 16 may range between 700 and 1200 pounds per square inch. From the receiver 16 the fluid 5 passes to a cooler 21 through the reduction valve 24 where its pressure is lowered. This pressure may be regulated as desired to operate at any pressure below that in the receiver. I have been able to operate at pressures as low as 500 pounds in the cooler. The cooler 21 is therefore filled with fluid under greatly reduced pressure from that in the receiver 16. Fluid from the receiver 16 under high pressure is passed through the line 15 19 and expanded through the expansion valve 22 into the coil 20 within the cooler 21. This expansion fluid cools the fluid in the cooler 21, which surrounds the coil. Any water which may be mixed with the carbon dioxide in the cooler is frozen upon the coils 20. The carbon dioxide therefore is dried and passes through the pipe 25 to the snow machine, where it is expanded to form snow or ice. By drying out the carbon dioxide in 25 the cooler 21 I remove all danger of freezing at the expansion valve in the snow machine. This enables me to operate the system under pressure much lower than that hitherto found possible with fluid which contained a portion 30 of water liquid with the liquid carbon dioxide.

The liquid from the receiver may be reduced in pressure from 700 to 1000 pounds per square inch to approximately 500 pounds, 25 and consequently is cooled to the saturation temperature corresponding to this pressure. By this reduction in pressure a certain amount of gas may be generated to cool the liquid, but, it is thought, the gas thus generated will be condensed into a liquid again 40 by means of the cold contact surfaces in the cooler. The abstraction of heat therefore required to cool the liquid from condenser temperature to any temperature corresponding to the saturated reduced pressure is then obtained from the cold contact surfaces 45 within the cooler, which not only perform this cooling but in addition cool the liquid down to the low temperature at which it passes to the snow machine.

50 The foregoing explanation should make it clear that the reduction in pressure through the pressure reducing valve does not involve any loss of energy at all.

55 It should be apparent that the secret of operating a system under a low pressure to the snow expansion valve is the use of a cooler for drying the carbon dioxide liquid prior to its expansion into the snow machine.

60 The reducing valve is a means for operating the system under pressures lower than those found necessary in methods and apparatus heretofore used.

65 New carbon dioxide fluid may be supplied to the system to replace that which has become

frozen into snow in any suitable way. For example, I may use the method shown and described in my co-pending application Serial No. 313,887, filed October 20, 1928, for Method and apparatus for manufacturing carbon dioxide ice from liquid carbon dioxide, which comprises a header 29 to which may be attached commercial carbon dioxide drums 30. The line 29 may be attached to the line 23 through which fluid under pressure in the drums may pass to the line 12 and then to the intake of the second stage compressor 13. Carbon dioxide from any source may also be drawn through pipe 31 directly into the line 11 and into the first stage compressor 10.

70 While I have shown this as a desirable way of admitting fluid to the system, I do not wish to be limited by this showing, as the system will operate with equal efficiency where gas from any suitable source is supplied to the system.

75 It will be obvious to those skilled in the art that various changes may be made in my device without departing from the spirit of the invention, and I, therefore, do not limit myself to what is shown in the drawing and described in the specification, but only as set forth in the appended claims.

80 Having thus fully described my said invention, what I claim as new and desire to secure by Letters Patent, is:

85 1. The method of making carbon dioxide snow which consists in compressing, cooling and condensing a fluid mixture of carbon dioxide and water, passing a portion of the fluid to a cooling chamber and simultaneously reducing its pressure, expanding another portion of the fluid in heat exchange relation with said cooling chamber to cool the low 90 pressure fluid therein and to freeze out the water content in the said fluid therein, the said freezing action operating to enable the fluid to be expanded at a low pressure through the expansion valve of a snow machine without freezing in the said valve, substantially as set forth.

95 2. The method of making carbon dioxide snow which comprises compressing and liquefying carbon dioxide gas, reducing the 100 pressure of a portion of said carbon dioxide and conducting said portion to a cooling chamber, expanding another portion from the condenser to cool the first named portion, and expanding the cooled portion to a snow machine, substantially as set forth.

105 3. The method of making carbon dioxide snow which comprises compressing, cooling and liquefying carbon dioxide gas, conducting the liquefied carbon dioxide to a receiver, 110 conducting a portion of the liquid from said receiver, reducing its pressure and delivering it to a cooler, expanding a portion of the liquid from said receiver to cool the carbon dioxide within the cooler, conducting the cooled 115

carbon dioxide from the cooler and expanding it to a snow machine, substantially as set forth.

4. The method of making carbon dioxide snow which comprises compressing, cooling and condensing a fluid mixture of carbon dioxide and water, reducing the pressure of a portion of said fluid, drying said fluid by freezing the moisture therefrom and conducting the said dried fluid to a snow machine and expanding it therein, substantially as set forth.

5. The method of making carbon dioxide snow which comprises compressing, cooling and condensing a fluid mixture of carbon dioxide and water, reducing the pressure of a portion of said fluid, and conducting said reduced portion to a cooler, expanding another portion of the fluid from the condenser to cool and dry the first named portion, expanding the cooled fluid to a snow machine to form snow, and conducting any unfrozen expanded carbon dioxide to the intake of the compression system, substantially as set forth.

6. In a system for making carbon dioxide snow having means for compressing and condensing a fluid mixture of carbon dioxide and water, a receiver, a liquid cooler means between the receiver and the cooler for reducing the pressure of the carbon dioxide as it enters the cooler and means in said liquid cooler for freezing out the water content of the liquid carbon dioxide whereby the carbon dioxide may be delivered through an expansion nozzle to a snow machine without freezing in the nozzle, substantially as set forth.

7. In a system for making carbon dioxide snow, a series of compressors, a condenser, a receiver, a liquid cooler, means for expanding the liquefied gas from the receiver into the liquid cooler to cool the same, another means for conducting fluid from the receiver to the liquid cooler, and pressure reducing means in the said latter means, substantially as set forth.

8. In a system for making carbon dioxide snow, having means for compressing, cooling and condensing carbon dioxide fluid, a receiver, a liquid cooler, means for conducting fluid from the receiver to the liquid cooler, means for reducing the pressure as the fluid passes from the receiver to the liquid cooler, means for expanding a portion of the fluid in said receiver to the said cooler to cool and dry the fluid in the cooler, and means for conducting fluid from the said cooler and expanding it to a snow machine, substantially as set forth.

In witness whereof, I have hereunto set my hand at Waynesboro, Pennsylvania this 16th day of January, A. D. nineteen hundred and nine.

FRANK R. ZUMBRO.
